[57] CLAIM

The ornamental design for a handbag handle, as shown and described.

DESCRIPTION

FIG. 1 is a front, top, right perspective view of a handbag handle showing my new design therefor;

FIG. 2 is a front elevational view thereof with the handbag shown in broken lines as environment only and forming no part of the design, two handles normally being used for a single handbag;

FIG. 3 is a side elevational view thereof, the opposite side being an identical mirror image;

FIG. 4 is a top plan view thereof;

FIG. 5 is a bottom plan view thereof; and,

FIG. 6 is a rear elevational view thereof.
